WEFT BOBBIN FOR ELECTRICAL FEELERS

Application filed July 9, 1930. Serial No. 466,707.

This invention relates to improvements in bobbins particularly adaptable for use with electrical weft detectors and also the method of making the bobbin and it is the general object of the invention to provide a bobbin having a contacting ferrule or the like which has the body portion of the bobbin cast therearound to hold the ferrule in position.

In the weaving of fine yarns it is desirable to have as smooth a surface on the bobbin as possible and it is a further object of the invention so to form the bobbin that there will be practically no groove or notch between the ferrule and the bobbin to entangle the last coils of the weft as they are unwound.

Another object of the invention is to provide a method for the making of the bobbin which includes a placing of the tapered ferrule in a mold prior to the introduction of the plastic or powdered material of which the bobbin is formed.

With these and other objects in view which will appear as the description proceeds, my invention resides in the combination and arrangement of parts hereinafter described and set forth in the claims.

In the accompanying drawings, wherein a convenient embodiment of my invention is set forth,

Fig. 1 is an elevation of a bobbin made according to my present invention,

Fig. 2 is a longitudinal central section through a bobbin shown in Fig. 1, and

Figs. 3, 4 and 5 represent diagrammatically the manner of carrying out the process of making the bobbin.

The bobbin B comprises a tapered yarn receiving barrel 10 terminating in a tip 11 and having at the opposite end a head 12. A ferrule 13 made of material capable of establishing electric contact between two oppositely charged detector elements 14 and 15, respectively, is securely fastened to the bobbin and has the surface thereof substantially continuous with the external surface of the body of the bobbin. Yarn retaining grooves 16 may be provided, and also a tapered bore 17 to receive the spindle of the winding machine.

The manner of making the bobbin is set

forth in Figs. 3, 4 and 5, where it will be seen that the mold 20 has a tapered bore 21 of a shape conforming to the external surface of the bobbin before the grooves 16 are cut therein. The mold may have wells 22 for receiving excess material in the upper portion thereof and there is provided a plunger 23 carried by a moving part 24 capable of being inserted into and withdrawn from the bore 21.

The walls of the bore are conical and conform to the shape of the conical external surface 25 of the ferrule 13. The proportions of the ferrule are such that when dropped into the bore 21 it will come to rest at the proper position, so that when later put in a loom it will cooperate with the electrodes 14 and 15. A light wooden or soft tool 26 may be used to tap the top end of the ferrule to hold the latter against accidental movement.

After the ferrule is placed in the bore as indicated in Fig. 3 a suitable amount of moldable material, such as powdered bakelite designated at 27, is poured into the bore as suggested in Fig. 4. The plunger 23 is then inserted into the bore and guided therein so as to lie centrally with respect thereto, said plunger having a taper to conform to that desired for the internal bore 17 of the finished bobbin. As the plunger moves into the bore the powdered material will rise and any excess will overflow into the well 22 to be removed after the bobbin is finished. Heat supplied by superheated steam may then be introduced into the chamber 28 surrounding the bore and the powdered mass melted into a homogeneous mass. This operation unites the ferrule with the bobbin and forces the bakelite around small ears 29 struck in from the surface of the ferrule to provide anchors. These ears are not considered necessary in all cases, as longitudinal movement of the ferrule is prevented by the wall 30 of the bobbin at the smaller end of the ferrule and rotation of the ferrule around the axis of the bobbin, if possible, will not be objectionable in all instances. In order to prevent looseness, however, with possible consequent resultant spacing of the ferrule from the shoulder 30 to define a groove into

which the thread might fall, I prefer to use the ears 29. After the bobbin has been formed it is removed from the mold and the grooves 16 cut circumferentially therein.

5 From the foregoing it will be seen that I have provided a simple form of bobbin having an electric contact surface held rigidly thereto by having the body of the bobbin case therearound. It will further be seen that the method of making the bobbin accurately positions the ferrule with respect to the ends of the finished bobbin and that there results a smooth yarn engaging surface from which the weft may be unwound without 10 danger of breakage. As the plunger moves into the mold the powder will be forced upwardly but the ferrule will be held in position by reason of the fact that it has previously been tapped so as to retain its position in the mold and resist any tendency to 15 rise with the compound 27.

Having thus described my invention it will be seen that changes and modifications may be made therein by those skilled in the 20 art without departing from the spirit and scope of the invention and I do not wish to be limited to the details herein disclosed, but what I claim is:

1. A bobbin having a yarn receiving surface composed in part by a metallic ferrule and in part by material molded around the ferrule. 25

2. A bobbin to cooperate with an electrical weft detector, the bobbin having a metallic ferrule and a body molded around the ferrule. 30

3. A bobbin to cooperate with an electrical weft detector having a metallic ferrule and having a body molded around the ferrule, 35 and held against relative angular motion with respect to the ferrule by projections on the latter extending into the body of the bobbin. 40

4. A bobbin having a tapered metallic ferrule forming a portion of yarn receiving surface thereof and having a body portion molded around the ferrule. 45

5. A bobbin having a tapered metallic ferrule forming a portion of the yarn receiving surface thereof and having a body portion molded around the ferrule, that portion of the bobbin other than the ferrule which receives the yarn having a surface substantially continuous with the surface of the ferrule. 50

6. A bobbin having a metallic ferrule which is tapered toward the tip of the bobbin, the bobbin having a body portion molded around the ferrule and having that portion thereof which has weft wound thereon 55 and is adjacent the tip end of the ferrule substantially continuous with the surface of the ferrule. 60

7. A bobbin having a tapered metallic ferrule and having a body molded around the ferrule, said bobbin having a head at the 65

large end thereof, the surface of the body adjacent that end of the ferrule near the head being substantially continuous with the surface of the ferrule.

8. A bobbin having a tapered metallic ferrule having large and small ends, the bobbin having a body which is molded around the ferrule and having yarn receiving surfaces which are substantially continuous with the surface of the ferrule at both the large and 70 small ends thereof. 75

In testimony whereof I have hereunto affixed my signature.

OSCAR V. PAYNE.
